UNITED STATES PATENT OFFICE.

CORNELL FLAGSTAD, OF MINNEAPOLIS, MINNESOTA.

BOX COVER AND FASTENING FOR SAME.

Application filed January 3, 1921. Serial No. 434,502.

To all whom it may concern:

Be it known that I, CORNELL FLAGSTAD, a citizen of the United States, residing at Minneapolis, in the county of Hennepin and State of Minnesota, have invented a new and useful Box Cover and Fastening for Same, of which the following is a specification.

My invention relates to box covers and fastening means for same. The main object is to provide a box or crate with an improved cover and means for holding the cover engaged with the box both when the box is set up and when it is folded in case it is a foldable box.

In the accompanying drawing: Fig. 1 is a top view of a box or a crate equipped with my improved cover and fastening. Fig. 2 is an enlarged section on the line 2—2 in Fig. 1, showing the box, however, as a folding box set up and also in dotted lines as folded. Fig. 3 is a top view of Fig. 1, or any other box having my cover and cover fastening means, in a certain modified form. Fig. 4 is an edge view of the cover and its fastening means in Fig. 3. Fig. 5 is a top view of the cover and fastening means further modified. Fig. 6 is a right hand end view of Fig. 5. Fig. 7 is an edge view of Fig. 5. Fig. 8 is a top view of the box with the cover and fastening means further modified. Fig. 9 is a partly sectional edge view of the cover and its fastening means in Fig. 8. Fig. 10 is a vertical section through a portion of the box and its cover showing in detail one form of the fastening means. Fig. 11 is a face view of the plate 30 in Fig. 10. Fig. 12 is another view like Fig. 10, but showing some modification in the box and fastening means for the cover. Fig. 13 is a top view of the socket 32 in Fig. 12. Fig. 14 is a face view of Fig. 13. Fig. 15 is a modification of Fig. 14. Fig. 16 is a face view of a hook-shaped substitute for either Figs. 11, 14 or 15. Fig. 17 shows the device in Fig. 16 applied to the box and its cover.

Referring to the drawing by reference numerals, 20 designates a hollow base in which side members 21, 22 and end members

23, 24 of the box are hinged at 20^a and other points (not shown), so as to fold upon each other, upon the bottom of the base as indicated in dotted line in Fig. 2, when the box is of the kind folding into a hollow base; but, as already stated, my invention is applicable also to unfoldable boxes.

In all the views where the box cover is shown it is designated by the numeral 25, and is preferably composed of several boards secured with their ends upon two parallel cleats 26, and an intermediate cleat 27, except in Fig. 3 where cleat 27 is omitted and a board 28 is secured with its ends to the underside of the right hand ends of the cleats 26, for a purpose presently to be described.

In all the forms shown one edge or end of the cover is provided with rigid fingers 29 adapted to be inserted in suitable catches fixed on the adjacent upstanding member of the box; said fingers 29 as well as the fingers 29^a at the opposite end or edge of the cover may preferably be hook-shaped as at 29^b, but for small boxes they may be plain, as to the left in Fig. 9, and they may be of either metal or wood. The catch or socket in which said fingers engage may each be either a plain plate as 30 in Figs. 10 and 11 with a hole 31 in it, or a socket as 32 with a hole 33 in it, or a plain bracket like 32^a in Fig. 15, though bulged forward at the middle the same as 32 in Fig. 13. Or, the catch on the box may be a mere hook, like 34 in Figs. 16 and 17. The form of catch 32 or 32^a is preferable in cases like Fig. 12, in which the wall 24 of the box has its upper portion offset outward by being formed as a reinforcing cleat 24^a, and the cover 25 or its cleats 26 rests upon the top of the portion 24 of the wall, the catch 32 serving to reach across a space which is created by making the cover so small that it will, when the box is folded pass down between similar catches 32^a (see Fig. 2) in the vertical part of the base and engage them with the same fingers 29 and 29^a.

In all the forms shown practically the entire cover is rigid and thereby very stiff and strong. Only at one end or edge of it the

fingers or locking members are in some way or other made tilttable so as to get them down into the box and then turned to horizontal position and engagement with the members fixed on the box.

This tilting arrangement is in Figs. 1 and 2 provided for by securing the fingers 29^a to a cross board 35, which is hinged at 36 to the cleats 26 (see Fig. 2) and is provided with a hole 37 for a post or projection 38 upon the cleat 27. Said projection having an aperture 39 for the insertion of a sealing wire or for the bail of a padlock placed as 40 in Fig. 1, when the cover is to be secured for a longer time. When the cover is to be put in place the fingers 29 are first inserted while the cover is at an incline, the board 35 is then tilted as in dotted line 35 in Fig. 2, while the fingers 29^a are inserted; the cover and the board 35 are then brought down to horizontal position and either a cotter pin (not shown) or a sealing wire or the padlock applied. To open and remove the cover requires simply a reverse operation to that just described.

In Figs. 3 and 4, where the board 35 is shown as open and resting in idle position upon the cover, said board is hinged at 41 to the adjacent board 25^x of the cover and the post 38 is fixed in a second folding board 42, or it may project through said board from board 28. The board 42 carries the finger 29^a and being hinged at 43 upon the cross board 28 it may fold flat down upon the latter between the cleats 26. This being done the board 35 is folded upon board 42 and secured to post 38 the same as described about Figs. 1 and 2. In the cheapest construction pegs 43^x or other obstructions against the edge of board 42 take the place of the hinges 43.

In Figs. 5, 6 and 7 each finger or catch member 29^a is an independent beam-lever hinged near its middle, as at 26^x, to one of the cleats 26, upon which one arm of the lever is held down by a board 35, hinged at 36, the same as in Figs. 1 and 2, when the outer arm or finger 29 of the lever is in the catch member on the box, and the board 35 is then folded down and secured as in Fig. 1, only that it folds in the opposite direction.

In Figs. 8 and 9 the fingers 29^a are secured across the underside of a board 35, which is hinged at 43 to the cleats 26 and is held down flat upon cleats 26, 27 by the board 42^a, which is hinged at 41 and arranged to fold upon the cleats between the boards 35 and 25^x and thus rest upon the projecting portions 29^x of the members 29^a. The post 38 and hole 39 are the same as in Figs. 1 and 2.

In Fig. 1, 44 designates a pivoted hook adapted to be engaged in the aperture of the post 38 as a temporary locking means. The main advantages of the invention are

that the fingers on the cover are tilttable and hook shaped so that they may be engaged as hooks and thus resist spreading or bulging of the walls of the box when the latter is packed with goods. In this connection it will be understood that the hook fingers may be increased in numbers according to the size of the box; and that their shape may be considerably altered without diverging from the spirit and scope of the invention, the main features of which reside in the construction of the cover.

What I claim is:

1. The combination with a box or crate having two opposite body members provided with catch members, of a cover having at one end rigid catch members adapted to engage the adjacent catch members on the box, the other end of the cover having catch members hingedly secured to the cover so as to enable them to tilt downward into the box and then be tilted into engagement with the adjacent catch members on the box, and means for holding said tilttable members in engaged position.

2. The structure specified in claim 1, said catch members on the cover having their outer ends formed with upwardly curved hooks adapted to take hold of the catch members on the box, to prevent spreading of the latter or disengagement of the members.

3. The structure specified in claim 1, the means holding the tilttable catch members engaged comprising a board hinged to the cover and arranged to fold flat upon the tiltting members, and an element projecting upwardly from the cover through the hinged board and means engaging the projecting element to prevent raising of the board.

4. The structure specified in claim 3, said tilttable members being secured together so as to tilt simultaneously.

5. The structure specified in claim 2; said box having a hollow base and its wall-sections hinged to be folded into the base; the wall sections carrying the catch members having each in its top a recess for the cover to rest in, and the catch members on said wall sections being projected partly across the recess so as to reach and engage the catch member on the cover; said base having inside its vertical portion catch members adapted to be engaged by the catch members on the cover when the latter is placed upon the folded box sections in the base.

6. In a folding box or crate, the combination with a base provided with catches, of foldable body sections, two of said body sections being provided with catches, a cover having on one edge rigid catches adapted to engage the adjacent catches on the box or crate, and on another edge tilttable catches adapted to be tilted into engagement with the adjacent catches on the box, the catches

in said body sections being adapted to receive the cover catches when the sections are set up in vertical position, and said catches in the base being adapted to receive the same cover catches when the body sections are folded and the cover placed upon them.

7. The structure specified in claim 6, and means for holding said tilttable catches in engaged position.

10

In testimony whereof I affix my signature.

CORNELL FLAGSTAD.
